UNITED STATES PATENT OFFICE.

JOHN SHARSHALL GRASTY AND WALTER SHELDON RODMAN, OF UNIVERSITY,
VIRGINIA.

METHOD AND APPARATUS FOR LOCALIZING MINE EXPLOSIONS AND FIRES.

1,261,924.

Specification of Letters Patent.

Patented Apr. 9, 1918.

Application filed August 25, 1914. Serial No. 858,545.

To all whom it may concern:

Be it known that we, JOHN SHARSHALL GRASTY, a citizen of the United States, residing at University, county of Albemarle, 5 and State of Virginia, and WALTER SHELDON RODMAN, a citizen of the United States, and resident of the same place, have invented certain new and useful Improvements in Methods and Apparatus for Localizing 10 Mine Explosions and Fires, of which the following is a specification.

Our invention has for its object to provide a system of barriers for the localization of mine-explosions, and of fires resulting therefrom, by placing at suitable points in the mine, screens or barriers which, while permitting the passage of the pressure, due to explosion, will check the passage of the explosion itself, these screens or barriers being of such a character that they are normally out of the way, but are automatically interposed in the passage or air-tunnels upon the occurrence of an explosion, and in time, to intercept the advancing way of the explosion along such passage. For these purposes, 15 it consists of suitable screens of wire gauze, preferably used in groups, with means for automatically closing such screens from a distance, upon the occurrence of an explosion adjacent to such closing means, the closing means being of such a nature that the time of action thereof is less than that taken for the travel of the explosion from the point where closing means are located to 20 the screen. Inasmuch as the propagation of the explosion is extremely rapid, this requires that the closing apparatus have a short time constant. The invention further consists in the construction, combination and arrangement of the several parts of 25 which it is composed, which will be herein-after more fully described and claimed.

Referring to the accompanying drawings, in which corresponding parts are designated 30 by corresponding marks of reference,—

Figure 1 is a typical representation of a mine having our invention applied thereto.

Fig. 2 is an elevation of one of the barriers used therein.

Fig. 3 is a section through the barrier 50 shown in Fig. 2.

Fig. 4 is an elevation of the barrier-release which may be employed.

Fig. 5 is a plan view thereof.

Fig. 6 is a wire diagram.

In carrying out our invention, the barriers A are located at suitable points in the passage-ways of the mine to be protected, such barriers being normally held opened by electrically-controlled mechanism, the circuit-controllers C for which are located in the mine at points where explosions are liable, and against which explosions it is desired to protect. In practice, this distance should not be less than two hundred feet 65 from the barriers to be controlled thereby, so that upon an occurrence of an explosion adjacent to any of the circuit-controllers, the barrier or barriers controlled thereby will be dropped across the passage-ways. 70

The barriers A, in their most perfected form, comprise suitable pivoted frames 1, preferably of iron, adapted to fit within casings 2 anchored in the passage-ways. These casings are, by preference, as near flush as 75 may be with the walls of the passage-ways so as to reduce as much as possible, the surfaces retarding the flow of the air in front of the explosive-waves, and the frames fit therein sufficiently tight to prevent the passage 80 of flame between them.

The frames 1 carry screens 3 of fine-wire mesh. In Fig. 3, we have represented three such screens carried in a single frame. As shown there, the outer screens are of copper 85 or bronze wire, and are of about fifty-mesh, while the central screen 3^A, is of about 100 mesh. In Fig. 2, we have further shown these outer screens as protected by a coarse wire-netting, in order to afford a support 90 therefor and protect the same from flying fragments. In the barrier shown in Figs. 2 and 3, there is, by preference, an interval of about two inches between each of the screens 3 and 3^A.

The frame above described, is by preference pivoted at its upper edge within the casing 2, and is normally maintained in its

raised position, and in the top of the passage-way, by means of a lip 2^A on its lower edge engaging one end of the armature 5, which is fulcrumed on the anvil 6 hung from the roof of the passage-way, the opposite end of such armature being normally held down by the attractive pull of an electro-magnet 7. Thus, as long as there is sufficient field of force surrounding the magnet, the frame will be held raised, while, upon the breaking of the circuit energizing the electro-magnet, the barrier will fall, and close the passage-way. Its movements in this, may be accelerated in any way that it is desired. By pivoting the door on the side of the casing on which the explosion is liable to occur, no mechanism will be needed to hold the door closed when lowered against the pressure of the advancing wave.

20 The winding of the electro-magnet 7 is included in a control-system, in which is a circuit-controller C, located, as before stated, at some distance from the barrier. The circuit-controller may take many forms. In the form of the invention shown herein, the circuits are closed circuits, and therefore the controllers are circuit-breakers. They may be either fusible, thermostatic, or pressure-actuated. The fusible circuit breakers will be easily fusible links placed in the electric-circuit at such strategic points as may be necessary. The thermostatic and the pressure actuated controllers can be of the type now used in automatic fire-protection practice.

In Fig. 6, we have shown a wiring diagram. In the circuit *a* of that figure, there is a controller for the single barrier releaser shown therein. In circuit *b* there are two controllers for a single barrier releaser, and in circuit *c*, there is a single controller for two barrier releasers, all of the several circuits being branched from the main lines D and E. It is obvious that the location of the controllers and of the barriers and the association made between the several controllers and the barriers, is dependent upon the conditions of each installation, and will be determined by the engineer in view of those conditions, the essential point of our invention being the utilization of fine mesh screens to stop the passage of flame in explosions. In this connection, it is proper to observe that we have ascertained that the use of screens in tandem, such as we have here disclosed in Figs. 2 and 3, produce a markedly different result from the use of a single screen, and this, although the screens are not placed in contact with each other, but are separated by an interval. We are not at this time able to explain the reason for this beneficial effect of the separated screens in tandem, but we find that with an explosive mixture located on both sides of

the barrier, as well as between the screens thereof, and an explosion taking place in the explosive mixture to one side of the screen, such explosion is not communicated through the barrier, although with a single screen and an explosive mixture on each side thereof, the explosion to one side of the screen would be transmitted to the opposite side thereof. It appears as if the gases trapped between adjacent and non-contacting screens act as a barrier to the transmission therethrough of an explosion from one side to the other, and we particularly point out this feature as an important one of our invention. It will be noted that between the screens of fine mesh a dead air space is formed, that is to say, one having no communication with the outside of the barrier, save through the interstices of the screens.

Having thus described our invention what we claim and desire to secure by Letters Patent is:—

1. As a barrier against the propagation of an explosion in an explosive atmosphere, a plurality of screens arranged in tandem in the path to be protected against the passage of the explosion through such atmosphere and out of contact with each other and having an air space between them.

2. As a barrier against the propagation of an explosion in an explosive atmosphere, a plurality of screens arranged in tandem in the path to be protected against the passage of the explosion through such atmosphere and out of contact with each other and having a closed air space between them.

3. In an apparatus of the character described, the combination with a passage-way to be protected against the propagation of an explosion through an explosive atmosphere contained therein, of a barrier located in such passage-way and separating the explosive atmosphere in such passage-way on opposite sides thereof, such barrier including a plurality of wire screens arranged in tandem and having a closed air space between them.

4. In an apparatus of the character described, the combination with a passage-way to be protected against the propagation of an explosion through an explosive atmosphere contained therein, of a barrier located in such passage-way, and separating it into compartments having no communication with each other except through such barrier, the barrier including a plurality of wire screens arranged in tandem in the passage with an air space between them.

5. In an apparatus of the character described, the combination with a passage-way to be protected against the propagation of an explosion through an explosive atmosphere contained therein, of a barrier including a plurality of wire-screens arranged in

tandem adapted to be moved into position to separate the passage-way into sections having no communication with each other, except through such barrier, and means located at a distance from such barrier, actuated upon an explosion in the vicinity thereof to move such barrier.

6. The hereinbefore described method of arresting explosion of inflammable air in the passage way of a tunnel, which consists in interposing in the path of such explosion a film of the inflammable air contained between partitions of wire netting extending entirely across the said passage.

In testimony whereof we hereunto affix 15 our signatures in the presence of two witnesses.
